AUTOMATIC ENGINE STARTING APPARATUS

Thomas D. Joeck, Eatontown, N. J., assignor to the United States of America as represented by the Secretary of the Army

Application July 11, 1955, Serial No. 521,429

7 Claims. (Cl. 123—179)

(Granted under Title 35, U. S. Code (1952), sec. 266)

The invention described herein may be manufactured and used by or for the Government for governmental purposes without the payment of any royalty thereon.

This invention relates to automatic apparatus for controlling a supply of high energy dry fuel during successive stages in the starting and warming up cycle of internal combustion engines.

Initial starting of internal combustion engines particularly at low temperatures has presented many serious problems. Most of the difficulties encountered relate to the problem of converting liquid hydrocarbons to highly inflammable vapor or near vapor which is both dry and contains a high percentage of hydrocarbon. The difficulties are magnified by low ambient temperature conditions which create a natural state within the liquid fuel increasing its resistance to vaporization. Various means have been employed to suitably condition the fuel for starting, such as injecting or radiating substantial quantities of heat at the point of vaporization. Such means is highly inefficient since substantial quantities of power or fuel are required for auxiliary heating. Moreover, in many circumstances means for obtaining the necessary heat is not available.

The conventional manner of providing suitable fuel mixtures for starting engines is the provision of an atomizing nozzle through which a quantity of priming liquid fuel is forced during the starting period, the priming fuel being supplied in addition to that supplied by the vaporizing means which functions during the normal operation of the engine. In such a system the fuel air ratio is adjusted to provide a rich mixture within the cylinders. A mixture provided in this manner although rich in fuel is not efficient because of its so-called "wet" character. In such a wet mixture large droplets of fuel are present which fail to vaporize and therefore do not completely burn. Carbon deposits which result from such incomplete combustion cause serious trouble in the engine and must frequently be removed.

The present invention overcomes the above deficiencies of conventional systems and provides a novel means for supplying high energy efficient fuel during the complete starting cycle. The invention includes means for conditioning fuel which reduces the size of the droplets to such small dimensions that vaporization is highly accelerated and the mixture thus derived closely approaches a complete vapor. This result is accomplished without the application of heat and furthermore the device is effective at extremely low temperatures as low as 65° below zero Fehrenheit. The broad principle of finely dividing the liquid fuel is disclosed in my United States Patent No. 2,532,554.

In the present invention the above stated principle of conditioning fuel for starting is incorporated in an apparatus which automatically adjusts a plurality of controls to provide reliable starting, smooth operation of the engine during the warming up period and then converts the engine to normal operation.

Automatic control for the apparatus is accomplished

2

through a heat responsive mechanism which when cold conditions the whole system to respond to cranking of the engine in such a manner that high energy inflammable fuel is supplied to the engine and as the engine warms up to the temperature where the enriched fuel is no longer required the system is automatically converted to normal operation by a conventional carburetor.

It is a primary object of the invention to provide an apparatus for rapidly and efficiently starting an internal combustion engine.

A further object of the invention is to provide an automatic engine starting system in which the fuel mixture fed to a cold engine is subjected to atomizing means capable of reducing the liquid fuel to a condition closely approaching true vaporization without the application of heat.

A still further object of the invention is to provide a completely automatic apparatus capable of starting an internal combustion engine at very low temperatures and subsequently converting to normal operation of the engine by a conventional carburetor.

A further object of the invention is to provide an automatic mechanism acting to coordinate the means for supplying an enriched fuel mixture during the initial phase of starting the engine, with means for converting to normal operation by a conventional carburetor and further to automatically restore the controls to their cold starting adjustments after a period of idleness of the engine.

Other objects and features of the invention will more fully appear from the following specification and will be particularly pointed out in the claims.

To provide a better understanding of the invention a preferred embodiment thereof will be described and illustrated in the drawings in which

Fig. 1 is a side elevation of the apparatus showing a portion only of the engine.

Fig. 2 is an enlarged detail of the automatic means for controlling the supply of fuel to the engine for starting purposes.

Fig. 3 is a partial view of the mechanism shown in Fig. 2 illustrating the position of the elements thereof during a different phase of the starting cycle from that shown in Fig. 2.

Fig. 4 is a cross-section on line 4—4, Fig. 5 showing the details of the liquid fuel valve.

Fig. 5 is a cross-section on line 5—5, Fig. 1.

Fig. 6 is a cross-section on line 6—6, Fig. 2 showing the details of the heat controlling mechanism.

In Fig. 1 of the drawings the invention is shown applied to a gasoline engine equipped with an intake and exhaust manifold 10 to which a conventional carburetor 11 is secured. The carburetor feeds fuel to the lower section of the manifold 10 which contains the intake ports for the engine while the separate upper section of the manifold communicates with the exhaust ports of the engine. The remaining portions of the engine are not shown since their construction may be conventional and their function does not relate directly to the invention.

Fig. 1 of the drawings illustrates the moveable elements of the apparatus in the position they assume when the engine has been idle and its temperature has reached or substantially reached that of the surrounding air. At this time the main throttle valve 12 has been opened by an engine speed governor to which it is connected. The governor is not shown but it is connected to the valve 12 by a crank 13 secured to the pivot shaft of the valve and a connecting link 14 pivoted to the end of the crank 13.

Under certain circumstances, for example, if it were desired to control the engine manually by operation of the valve 12, this valve could serve the double purpose

of a main control for the engine and also to close the passage to the conventional carburetor during the operation of the novel starting equipment to be described. In the specific application of the invention presented herein, however, the operation of the engine is made as automatic as possible. Therefore, the device illustrated herein is adapted to be operated in connection with a speed governing device which actuates the valve 12 in accordance with the power demands of the engine. In such governing devices the valve is open while the engine is idle and therefore is shown in its open position in Figs. 1 and 5.

For proper operation of the starting means at this time the fuel passage from the carburetor 11 must be closed or very nearly closed. To close this passage, therefore, another butterfly valve 15 is situated in the passage and its operation is controlled by the starting apparatus. At the beginning of the starting and warm-up period the valve 15 is closed as shown in Fig. 5. When the engine is cranked, therefore, a relatively high vacuum is created in the intake manifold 17. This condition causes a rapid flow of air through a fuel conditioning device 18 having an air inlet conduit 19 connecting it to the outer air or to an air cleaner 20. The device 18 desirably is received in a threaded aperture in the wall of the intake manifold and is supplied with liquid fuel from a pipe 21 in a manner to be specifically described.

The fuel conditioning means 18 supplies an enriched dry mixture of fuel and air to the engine during the starting and warm-up period and is described in detail in an application by the present inventor filed in the U. S. Patent Office on January 5, 1954, bearing Serial No. 402,419. Liquid fuel is fed to a chamber 22 within the body 23 of the device 18 through the pipe 21. At the same time air flows thereto from the conduit 19. The supply of air enters the chamber 22 through an annular jet 24. The fuel and air are mixed in the chamber 22 and pass into the intake manifold of the engine. The dimensions of the chamber 22 are so adjusted that the air entering the chamber at substantial velocity sets up supersonic vibrations within the chamber which violently agitate the mixture in the resonance chamber 22. This agitation subdivides the fuel droplets to a size so small that in effect the mixture emerging from the chamber is substantially equivalent to a vapor which is readily ignited and burns completely and instantly within the cylinders.

To utilize to the fullest extent the advantages of the fuel conditioner 18, the present invention coordinates additional elements therewith in a novel manner which renders the complete starting cycle of the engine substantially automatic. The complete cycle referred to includes initial starting of a cold engine, warming up the engine and converting from the specialized starting elements to operation by a conventional carburetor after normal temperature has been reached.

To accomplish this result the flow of fuel through the conditioner 18 is controlled to accord with the demands of the engine during the various phases of its starting cycle. Also the valve 15 is automatically adjusted to coordinate the system when converting from operation of the engine by enriched starting fuel mixtures to operation by the conventional carburetor 11.

In the interest of compactness and adaptability the liquid fuel controlling means and the valve 15 are received in a unitary body member 25 having flat parallel sides which permit it to be received between the flange 26 of the intake manifold and the flange 27 of the carburetor 11. The member 25 is clamped in position in any suitable manner such as by suitable clamping bolts. Other arrangements may be provided to adapt the controlling mechanism to the engine.

The member 25 is provided with an aperture 28 which registers with the main fuel conduit from the carburetor 11 to the manifold 10. The valve 15 is received within the aperture 28 and is supported upon and rotated by a

shaft 29 extending diametrically across the aperture 28. One end of the shaft 29 projects from its bearing to receive an actuating member to be described hereinafter. The other end of the shaft 29 projects into the chamber of a fuel valve formed in the member 25 and shown in detail in Fig. 4 of the drawings. The valve is provided with a chamber 30 at one end thereof within which is received a closure member 31 which is forced against the valve seat by a compression spring 32 received at one end in a recess in the closure 31 and is seated at its other end against a fitting 33 to which is connected a tube 21 which in turn is connected to the conditioner 18. The closure 31 cuts off the flow of fuel by engaging a seat 35 in the valve body 25. To provide a tight seal when the valve is closed a toroidal member 36 of rubber or other yieldable material is provided. The closure member 31 is of slightly less diameter than the chamber 30 to permit free flow of liquid when the valve is open and also to meter the quantity of fuel passing therethrough. Fuel enters the valve through the fitting 38 and the aperture 37. To operate the valve closure 31, the end 39 of the shaft 29 is flattened at 40 to present the cam face which engages the extension 41 of the closure 31. Rotation of the shaft 29, therefore, actuates the closure into its open and closed positions.

A thermostatic means is provided for automatically controlling the supply of starting fuel to the engine in response to engine temperature. The necessary movement for such control is provided by the expansion and contraction of a bimetallic member 42 which is housed in a heat chamber 43. The chamber may be constructed in any suitable fashion. As shown the sheet metal cover 44 is secured to a base plate 45 which in turn is secured to the exhaust manifold 46. An aperture in the manifold 46 registers with an aperture 47 in the plate 45. Secured to the plate 45 is a hot gas controlling and deflecting device 48. This device is composed of a body 49 having an aperture therein positioned to register with the aperture 47. The upper portion of the member 49 is cut away for substantially one half of its thickness and a cover plate 50 is secured thereto to present a fan-shaped upwardly directed channel 51 through which hot gases from the exhaust manifold are directed against the bimetal 42 which in turn is arched over the assembled member 48 as shown in Fig. 2. In this position the bimetal is in the direct path of the gases from the exhaust manifold.

One end of the bimetal 42 is rigidly fixed to a bracket 52 secured to the plate 45 while its other end is secured to an arm 53 which moves with the bimetal as its temperature changes and imparts such motion to a link 54 which in turn is pivoted upon a connecting lug 55 adjustably fixed to a plate 56 which will hereinafter be termed a program plate because it determines the extent of rotation of the shaft 29 at different times in the complete starting and running cycle. The lug 55 is adjustable along the left hand end of plate 56 and is secured in position by a suitable set screw.

Means are provided for opening and closing a valve 57 situated in the opening through the member 49, the plate 45 and the aperture leading to the exhaust manifold. This valve desirably is of the butterfly type and is secured to a shaft 58 pivotably received in the member 49. The lower end of the shaft has secured thereon a small crank 59 having a link 60 pivoted at one end to the pivot pin of the crank and pivoted at its other end to the moving end of the bimetal member at 61.

The program plate is guided in a straight horizontal path and supported by a pair of pins 62 rigidly secured in the member 25 which ride in slots 63 as the plate moves. The plate is also provided with a slot 64 in which the shaft 29 is received. The plate 56 coacts with a sector member 65 secured to and rotating with the shaft 29. The sector has secured therein a pair of spaced pins 66 projecting perpendicularly from its face into a position wherein the pins will engage a plurality of control surfaces

formed in the plate which act to limit and control the position of the sector 65 in a manner to be described in connection with the description of operation of the apparatus to be presented hereinafter.

A still further control is effected through electromagnetic action. When the starting switch 67 is closed current from the battery 68 flows to the starting motor and also in the circuit 69 which energizes the magnet 70. A switch 71 is provided which normally is closed but may be opened to render the electromagnetic means inoperative. The magnet 70 when energized acts upon an armature 72 pivoted at 73 upon the frame 74. The armature has an extension 75 to which a link 76 is pivotally connected. The other end of the link is pivoted at 77 to a short arm extending from the sector 65 so that actuation of the magnet tends to rotate the shaft 29. When the magnet is energized the downward motion of the armature is limited by a stop 78. The link 76 is of special construction and is composed of two telescoping sections which are yieldingly held in relative axial position by a tension spring 79 received in an enlarged cylindrical chamber in the lower section. The lower end of the upper section is provided with a head portion 80 movable in the chamber and to which one end of the spring is secured. The other end of the spring is secured to a removable cap 81 within which the upper link section is slidably received.

In describing the operation of the apparatus it will be assumed that the engine has been idle for a substantial period and has assumed ambient temperature which may be very low such as temperatures found in arctic regions. At this time all of the elements of the device have assumed the positions shown in full lines in the drawings with the exception of Figs. 3 and 6. The bimetal 42 has moved the plate 56 into its right hand position and the link 69 and crank 59 have opened the valve 57. Also at this time a projection or cam member 82 has engaged the right hand pin 66 on the sector 65 to rotate the shaft 29 clockwise which opens the valve 25 and admits liquid fuel to the conditioner 18 and also closes or substantially closes the valve 15.

In Fig. 1 of the drawing the switch 67 is shown closed which draws the link 76 into its extreme downward position at which time the segment 65 is given a slight movement in addition to that derived from the plate 56 which substantially closes the valve 15 shown by the dotted position of the pins 66. Prior to the cranking period the valve assumes a slightly open position which is its correct position for the warming up phase of the complete cycle as shown by the full line position of the pins in Fig. 2. This slight movement is permitted by a slotted portion 83 of the plate 56.

During the cranking period a high vacuum is created in the intake manifold 17 which causes a rapid flow of air and a consequent flow of fuel in the conditioner 18 where a highly efficient rich and dry fuel is developed through the supersonic action referred to. This fuel passes into the intake manifold and thence to the engine cylinders where it is readily ignited and burns completely thus developing sufficient power to start the engine even though its temperature is very low.

When the engine is thus started the starter switch is opened and releases the armature 72, which frees the sector 65 which moves the valve 15 counter-clockwise into the position represented by the full line position of the pins 66. This movement is due to spring action to be described. Thus slightly more air enters the system through the carburetor 11 whose valve 12 is at least partially opened by the governor since the engine is now running slowly.

During this phase of the starting cycle the heated gases in the exhaust manifold are permitted to enter the chamber 43 and act to heat the bimetal 42 which starts to move the plate 56 toward the left. During the warm-up period this movement permits the sector 65 and thus the valve 15 to gradually open under the action of a spring 84 which moves the armature 72 upward a sufficient distance to

tension the spring 79 in the link 76. When a point is reached in the counter-clockwise rotation of the sector and valve where the right hand pin 66 rides over the outer end of the projection 82 the spring is free to quickly open the valve 15 to its maximum open position determined by the arrival of the left hand pin 66 at the bottom of the slot 85 as shown in Fig. 3. At this time the bimetal has been heated to the temperature where it has moved the plate 56 into its hot running position shown in Fig. 3, and the valve 25 is closed. Thus the starting mechanism ceases to function and the engine may now be operated by the carburetor 11 either manually or by means of a governor through the link 14 connected to the valve 12.

Assuming another condition wherein the engine is stopped and again started while it is still at maximum temperature or partially cooled. To start the engine under the above conditions the starting switch is closed which pulls down the link 76 and rotates the valve 15 against the action of the spring 84 until the right hand pin 66 engages the upper edge 85 of the plate 56 as shown in Fig. 3. This position is calculated to be an intermediate position between closed and wide open position of the valve and just sufficient to start the hot engine. At this time the governor will have opened the main valve 12. Since the armature 72 and its extension 75 tend to move into their extreme bottom position the over riding motion thereof beyond that at which the pin 66 engages the plate 56 is provided for by the spring 79 in the link 76.

When the starting switch is again opened the segment 65 will return to its hot running position and normal operation of the engine will resume.

What is claimed is:

1. In combination with an internal combustion engine having a carburetor and an intake manifold, an automatic engine starting apparatus comprising a starting fuel conditioning means having liquid fuel and air supplying connections and a resonance chamber wherein fuel and air are vibrated at supersonic frequency, connection from the output of said conditioning means to said intake manifold, starting fuel controlling means including a choke valve and a liquid fuel valve, means simultaneously to close said choke valve and open said liquid fuel valve, a heat sensitive actuating means responsive to engine temperature, means connecting said heat responsive means to said starting fuel controlling means, said heat sensitive means being adjusted to close said choke valve and open said liquid fuel valve, when the engine is cold and to reverse the valve positions when the engine assumes hot running temperature, and means communicating from said choke valve opening to said carburetor.

2. In combination with an internal combustion engine having a carburetor and an intake manifold, an automatic engine starting apparatus comprising a starting fuel conditioning means having liquid fuel and air supplying connections and a resonance chamber wherein air and fuel are vibrated at supersonic frequency, a connection from the outlet of said fuel conditioning means to said intake manifold, starting fuel controlling means including a choke valve operable to close the connection from said intake manifold to said carburetor and a liquid fuel valve operable to control the flow of liquid from a source of fuel, means simultaneously to close said choke valve and open said liquid fuel valve, a heat sensitive valve actuating means responsive to engine temperature, means connecting said heat responsive means to said starting fuel controlling means, said heat responsive means being adjusted to close said choke valve and open said fuel valve when the engine is cold and to reverse the valve positions when the engine has assumed hot running temperature, means connected to said heat responsive means acting to limit the movement of and hold said starting fuel controlling means in a plurality of predetermined positions determined by the temperature of the engine.

3. In combination with an internal combustion engine having an intake and exhaust manifold and a carburetor connected to the intake manifold, an automatic engine

starting apparatus comprising a starting fuel conditioning means having liquid fuel and air inlet connections and a resonance chamber therein in which the air and fuel are vibrated at supersonic frequency, a connection to feed the conditioned fuel to said intake manifold, starting fuel controlling means including the choke valve operable to close the connection from said intake manifold to said carburetor and a valve to control the flow of liquid fuel to said conditioning means from a fuel supply, means operable simultaneously to close said choke and open said liquid valve, a bi-metallic member responsive to engine temperature, means connecting said bi-metallic member to said starting fuel controlling means, said bi-metallic means and its connection being adjusted to close said choke and open said liquid valve when the engine is cold and to reverse the valve positions when the engine has assumed hot running temperature, a movable program plate connected to and moving with said bi-metallic member, control surfaces on said plate acting to limit the movement of and to hold said starting fuel controlling means in positions corresponding to predetermined engine temperatures and a throttle valve in the conduit from said carburetor to said intake manifold operable to control the engine when it has reached hot running temperature.

4. In combination with an internal combustion engine having an intake and an exhaust manifold and a carburetor connected to said intake manifold, an automatic engine starting apparatus comprising a starting fuel conditioning means having liquid fuel and air supplying connections and a resonance chamber therein in which the fuel and air are vibrated at supersonic frequency, a connection to feed conditioned fuel to said intake manifold, a butterfly valve in the conduit from said carburetor to said intake manifold having an operating shaft, a liquid fuel valve situated adjacent said butterfly valve and having a closure member, an extension on said shaft operable to open said valve closure when said butterfly valve is closed and to close said liquid valve when said butterfly valve is open, an outside extension of said shaft having an actuating sector secured thereto, a bi-metallic member responsive to engine temperature, means connecting said bi-metallic member to said segment, said bi-metallic member and its connection being adjusted to close said butterfly valve and open said liquid valve when the engine is cold and through the action of said bi-metallic member to reverse the valve positions when the engine has assumed hot running temperature.

5. Automatic internal combustion engine starting ap-

paratus according to claim 4 together with a valve in the conduit from said carburetor to said intake manifold held open during starting and warm-up periods and operable to control the engine when it has assumed hot running temperature.

5 6. Automatic internal combustion engine starting apparatus according to claim 4 together with means operated by the said bi-metallic member acting to control the degree of heat of the engine to which said bi-metallic member is exposed, said means being adjusted for maximum exposure when the engine is cold and minimum exposure when the engine is hot.

10 7. In combination with an internal combustion engine having an intake manifold, a carburetor and an electric motor cranking means, automatic engine starting apparatus comprising starting fuel conditioning means having fuel and air supply connections and a resonant chamber in which the liquid fuel and air are vibrated at supersonic frequency, a connection from the outlet of said conditioning means to said intake manifold, starting fuel controlling means including a choke valve operable to close the connection from said carburetor to said intake manifold and a liquid fuel valve, valve actuating means operable simultaneously to close said choke and open said liquid valve, a heat sensitive means responsive to engine temperature, a connection from said heat sensitive means to said valve actuating means, said heat responsive means and its connection being adjusted to close said choke and open said liquid valve when the engine is cold and to reverse the valve positions when the engine has assumed hot running temperature, an electromagnetically actuated control means electrically connected to the starting motor circuit and having a magnetically actuated lever connected to said starting fuel controlling means, said lever acting when the starting motor is functioning to move said choke valve to its position of maximum closure, spring means acting to slightly open said choke when said starting motor switch is opened and a program plate moved into various positions by said heat sensitive means, said positions being determined by engine temperature, said program plate acting to establish said slightly open position of said choke while the engine is warming up, said program plate also having a stop surface thereon acting to establish a predetermined starting position of said starting fuel controlling means when the engine is restarted after it has assumed hot running temperature.
